ADJUSTABLE WINDOW SCREEN

Filed Aug. 23, 1922

Fig. 1.

Patented Dec. 4, 1923.

UNITED STATES PATENT OFFICE.

FRANK S. VERDONE, OF JOLIET, ILLINOIS.

ADJUSTABLE WINDOW SCREEN.

Application filed August 23, 1922. Serial No. 583,879.

To all whom it may concern:

Be it known that I, FRANK S. VERDONE, a citizen of the United States, residing at Joliet, in the county of Will and State of Illinois, have invented certain new and useful Improvements in Adjustable Window Screens, of which the following is a specification.

This invention has reference to adjustable window screens particularly designed to prevent the entrance of flies or other insects into a room or house, and its object is to make the screen adjustable to fit various sizes of openings without leaving any passages through which a fly or the like might gain entrance.

The invention comprises two sash adapted to fit into a window opening with one sash slidable with reference to the other whereby the screen may be made to adopt itself to various windows with the joints between the sash so arranged as to always maintain the opening closed against the flies or other insects irrespective of the area of the window.

The invention will be best understood from a consideration of the following detailed description taken in connection with the accompanying drawings forming part of this specification, with the understanding that the invention is not confined to any strict conformity to the showing of the drawings, but may be changed and modified so long as such changes and modifications mark no material departure from the salient features of the invention as expressed in the appended claim.

In the drawings:

Figure 1 is a perspective view of a partially extended fly screen,

Fig. 2 is a section on the line 2-2 of Fig. 1,

Fig. 3 is a longitudinal section of the fly screen shown in Fig. 1,

Fig. 4 is a detail perspective of a slide structure employed in the screen.

In the drawings there are shown two screen frames A and B which may be substantially alike and one slidable with relation to the other so that the area covered by the combined sashes may be extended or contracted as desired.

Each frame is of substantially U-shape and comprises an end rail 1, a top rail 2, and a bottom rail 3. The end rails are of greater thickness than the top and bottom

rails. The end rails are cutaway at each end to provide a seat 3'. The seats 3' on one end rail are oppositely disposed with respect to the seats 3' on the other end rail. 60 The top and bottom rails of each frame are mounted on the seats 3' of the end rails of each frame and secured in position by hold-fast devices 3''. When the frames are set up, the top and bottom rails of one frame 65 are slidably connected in a manner as hereinafter referred to, to the top and bottom rails of the other frame. The top and bottom rails of one frame are oppositely disposed with respect to the top and bottom 70 rails of the other frame.

The top and bottom rail of each frame is provided with a longitudinally extending slot 4 and the slots 4 are so set up that the slots of one frame will register with the 75 slots of the other frame. The slots are positioned between the upper and lower edges of a rail and extend from a point removed from the outer end and terminate at a point removed from the inner end of 80 a rail.

The inner edge of each end rail 1 is formed with a lengthwise extending groove 5', the lower edge of each top rail 2 is provided with a longitudinally extending 85 groove 5'' and the upper edge of each bottom rail is formed with a longitudinally extending groove 5. The grooves in the top and bottom rails register with the grooves in the end rails, and the said grooves 5, 5', 5'' of each frame have extended therein a foraminous sheet 6, such as metallic screen cloth and which is of such size as to terminate at a point removed from the free ends 90 of the top and bottom rails of the frame. 95

The screen frames are held together by slidable clip structures or plates 7 extending through registering slots 4 of the top and bottom legs. Two pair of clip structures are employed, one pair associating with the top rails of the frames and the other pair associating with the bottom rails of the frames. One of the clips of one pair is fixedly secured to one top rail and the other clip of the said pair is fixedly secured to the other top rail. One of the clips of the other pair is fixedly secured to one of the bottom rails and the other clip of said pair is fixedly secured to the other bottom rail. 100 One of the clip structures is shown separately in Fig. 4.

These plates 7 are made of metal of sheet

form long enough to extend transversely of two of the screen frames placed side by side with slit ends 8, 9, respectively, and the entire length of each plate 7 is such that the intermediate portion of each plate up to but not including the slit portions 8 and 9 equals the combined thickness of the two frames when placed face to face with the slit ends 8 and 9 projecting therebeyond.

10 The ends 8 and 9 are capable of being bent at right angles to the length of the plate 7 and against the outer faces of the contacting frame.

15 In order to provide a broad bearing surface for the split ends 8 and 9 on opposite sides of the rails 2, the split ends 8 are bent in opposite directions and the same is true of the split ends 9. The ends 9 are each provided with a countersunk screw hole 10 in 20 which is seated a wood screw 11.

Each frame A and B has the groove 5 of sufficient length and depth to seat the screen sheets 6 which are held in place in any suitable manner and move with the screen frame 25 to extend or retract the screen sections as a whole.

At the end of each section of the screen frame remote from the cross piece thereof, there is located a metal angle strip 12 having 30 return edges 13, 14, respectively, arranged at right angles one to the other to provide pockets 13', 14' respectively for the reception of the foraminous sheet 6 and a rubber strip 15 respectively. The return strip 13 embraces the corresponding edge of the screen mesh 6 carried by one frame and returned portion 14 grips a strip of rubber fabric 15 bearing against the screen mesh 6 of the other frame whereby to allow the two 35 frames to move one on the other and prevent 40

passage of flies or other insects between the screen meshes.

Each strip 12 is held to a respective leg 3 by means of a nail or pin 16.

What is claimed is:—

A window screen comprising a pair of U-shaped members shiftable relatively to each other and including top, bottom and end rails, the top and bottom rails of one member sliding against the top and bottom rails of the other member, each of said top and bottom rails provided with a longitudinally extending slot, a foraminous sheet secured to each of said frames, the slots of one frame aligning with the slots of the other frame, an upper pair of clips extending through the aligning slots of the upper rails, a lower pair of clips extending through the aligning slots of the bottom rails, said clips overlapping said rails, means for securing 55 one of the clips of said upper pair to one of said top rails, means for securing the other clip of the upper pair to the other top rail, means for securing one of the clips of the lower pair to one of the bottom rails, means 60 for securing the other clip of the lower pair to the other bottom rail, and a clamping strip interposed between the top and bottom rails of each frame at a point removed from the free ends thereof, each of said strips provided with a pair of pockets, one of said 65 pockets disposed at an angle with respect to the other and having seated therein said sheet, and a resilient member mounted in the other of said pockets, said members 70 abutting against said sheets.

In testimony whereof, I affix my signature hereto.

FRANK S. VERDONE.
